Primary Examiner — Derrick Holland*Assistant Examiner* — Lauren Calve(74) *Attorney, Agent, or Firm* — Leason Ellis LLP(57) **CLAIM**

The ornamental design for a shirt and tie arranged in a box, as shown and described.

DESCRIPTION

FIG. 1 is a front elevation view of a shirt and tie arranged in a box showing my new design;

FIG. 2 is a bottom plan view thereof;

FIG. 3 is a top plan view thereof;

FIG. 4 is a rear elevation view thereof; and,

FIG. 5 is a front elevation view of a shirt and tie arranged in a box shown in an alternate embodiment.

The broken lines of FIGS. 1-5 are for illustrative purposes only and form no part of the claimed design. The bottom, top, and rear views of the design shown in FIG. 5 are the same as the views shown in FIGS. 2-4. All sides not shown form no part of the claimed design.
